UNITED STATES PATENT OFFICE.

JEFFREY M. DAVIS, OF YOUNGSTOWN, OHIO.

FIRE-ESCAPE.

SPECIFICATION forming part of Letters Patent No. 287,910, dated November 6, 1883.

Application filed May 22, 1883. (No model.)

To all whom it may concern:

Be it known that I, JEFFREY M. DAVIS, a citizen of the United States, residing at Youngstown, in the county of Mahoning and State of Ohio, have invented certain new and useful Improvements in Fire-Escapes, of which the following is a specification, reference being had therein to the accompanying drawings.

My invention relates to an improvement in fire-escapes; and it consists in the combination of a fire-proof folding basket with a guide or way which is secured to the front of the building, suitable supporting-ropes by means of which the basket is raised and lowered, the pulleys over which the rope passes, and a suitable means for moving the basket back and forth in front of the building, as will be more fully described hereinafter.

The accompanying drawings represent my invention.

Figure 1 is a front elevation of the devices as applied to a building. Fig. 2 is a side elevation of the basket open. Fig. 3 is an end view of the same closed. Fig. 4 is a top plan view. Fig. 5 is a detail view, showing the swiveled pulley.

A represents a rail or rope extending from one side of a building to the other, supported by brackets under the cornice. On the rail 30 run two pulleys, b b', connected by a plate, c, under the rail. At the under side of the plate c is a swiveled pulley, d, and in the downward-bent ends of the plate are fastened the ends of a wire rope, e, that extend downward from both its sides.

B represents an oblong basket composed of two parts, hinged on the sides at the middle, so that the parts can be folded together when not in use. The basket is made of incombustible material, woven or interlaced to gain strength for carrying several persons at the same time, and deep enough to protect them from the flames when seated therein. At the bottom of the basket, where the two parts meet 45 when opened, is a catch that holds the parts together, by which the bottom is made as rigid as it would be if made of one piece. At both ends of the basket are guides f, through which passes the wire rope e, the upper ends of which 50 are attached to the plate c. The loose remaining parts of the ropes e under the basket are rolled on a light roller, g, to enable one per-

son to guide the basket, and the rope should be long enough that in case of great heat in front of the building the person holding it may stand at a safe distance. On the roller g is a loop for a pointed stake to pass through, which stake may be used, when stuck in the ground, to assist in steadyng or holding the basket. At the middle of the basket, extending from 60 side to side, is a rod, h, with an eye at its center, and to this one end of a wire rope, K, is secured. This rope K, after passing from the basket upward over the swiveled pulley d, reaches back to the ground, and is the means 65 by which the basket is raised or lowered while guided by the ropes e, and is shifted or drawn sidewise from one window to another wherever it may be wanted.

When not in use, the basket is folded together, inclosing the pending end of the rope K, and moved toward the corner of the front of the building or other suitable place, where a pin projects from the wall, and under it, at a proper distance, is hinged a false bottom, n, 75 of the size and form of one-half the bottom of the basket. On the projecting pin, of which the outer end is slightly bent, the basket is sidewise suspended. The roller g, around which the loose portion of the rope e is to be 80 wound, is placed in notches under the basket and the hinged false bottom raised. The pointed end of the stake is braced against the wall, and its upper end, with a hole through it, brought forward under the false bottom. When 85 in this position the basket, ropes, and stake are locked together and held by a padlock, to prevent irresponsible persons from interfering with the fire-escape.

It will be readily understood from the foregoing that as long as the walls of a burning building remain standing the basket can be brought to any window to assist in the escape of persons that may have remained in the building.

Having thus described my invention, I claim—

1. In a fire-escape, the folding basket B, substantially as described.
2. The folding basket B, in combination with the rope e, plate c, pulleys b b', swiveled pulley d; rope K, and rail A, substantially as shown and described.
3. The combination of the folding basket

with a hook which is made to catch in its side, and the sharp-pronged support which supports the basket from the under side, substantially as set forth.

5. The combination of the folding basket B with the guides f, ropes e, rod h, and a rope, K, which passes up over the swiveled pulley d, substantially as shown.

5. The combination of the folding basket, to provided with suitable notches or recesses, i,

in its edges, with the roller g, provided with a holding or steadyng device, and the ropes e, substantially as shown and described.

In testimony whereof I affix my signature in presence of two witnesses.

JEFFREY M. DAVIS.
